CHARLES C. MILLER, OF PITTSBURG, KANSAS.

STEAM-DOME SEPARATOR AND BOILER-SKIMMER.

1,239,931.

Specification of Letters Patent. Patented Sept. 11, 1917.

Application filed January 18, 1917. Serial No. 142,258.

To all whom it may concern:

Be it known that I, CHARLES C. MILLER, a citizen of the United States, residing at Pittsburg, in the county of Crawford and 5 State of Kansas, have invented certain new and useful Improvements in Steam-Dome Separators and Boiler-Skimmers, of which the following is a specification.

This invention relates to a steam skimmer 10 and separator, and more particularly to steam skimming and separating means adapted to be mounted directly in the steam dome of a boiler.

One of the main objects of the invention 15 is to provide skimming and separating means of the character stated adapted to cause the steam as it passes through the dome to travel through a tortuous path, the direction of travel of the steam being suddenly changed a number of times so as to 20 separate moisture from the steam. A further object is to provide skimming and separating means in combination with collecting and draining means, the separating means 25 being so shaped as to direct the moisture extracted from the steam into the collecting means. A still further object is to provide separating means of simple construction which can be readily applied to a steam 30 dome of standard construction. Further objects will appear from the detail description.

In the drawings:—

Figure 1 is a vertical central sectional 35 view taken through a steam dome and the contiguous part of a boiler with a separating and skimming means constructed in accordance with my invention applied,

Fig. 2 is a similar view taken at right 40 angles to Fig. 1,

Fig. 3 is a section taken substantially on line 3—3 of Fig. 1.

The boiler 1 is of standard construction, and is provided with the usual steam dome 2 secured thereto and communicating directly 45 with the interior of the boiler. The upper end of this dome is closed by the usual cap 3 having a central opening provided with a downwardly extending flange 4 concentric therewith, this opening being closed by means of the usual plate and yoke. Adjacent the upper end of the dome 2, and communicating therewith, are secured two diametrically opposite steam pipes 5. These 50 pipes serve to conduct the steam to the en-

gine cylinders, or any other point where it is desired to utilize the steam.

Mounted within the dome 2, intermediate the lower end thereof and the steam pipes 5, are a plurality of baffle plates 6, 7, and 8, 60 Each of these plates is of approximately sectoral shape in top plan view, and is concaved longitudinally, that is, for its greatest length. Each of these plates fits snugly the interior of the dome 2 and extends somewhat 65 over half way across the same, the length of the minor axis of each plate being greater than the radius of dome 2, the plates 6 and 8 being disposed above and below the plate 7, and being oppositely directed thereto and 70 having their minor axes in the same vertical plane as the minor axis of plate 7. By this means, the baffle plates are mounted in spaced super-posed and overlapping relation so that, as the steam flows into and 75 through dome 2 it has its direction of travel suddenly changed and flows between plates 6 and 7, and plates 7 and 8, finally escaping through the pipes 5. As is well known, this 80 sudden change in direction of flow of the steam causes precipitation of the moisture carried by the steam, thus separating this moisture which collects on the plates. Also, due to the fact that the under faces of the 85 plates are concaved, as the steam rises it tends to crowd toward the highest point or crown of each plate, this resulting in changing, to a certain extent, the direction of flow 90 of steam from a vertical flow to a more or less horizontal flow, this change in direction of flow also serving to separate a certain amount of moisture from the steam. By this means, I insure that practically all moisture 95 will be separated from the steam before it enters the steam pipes 5, thus avoiding the loss of energy and, in some cases, the serious injury caused to the piston rods, cylinders, and other parts of the engine, due to excessive moisture being carried by the steam into the engine cylinders and connections. 100

In addition to serving as separating means, in the ordinary sense, for separating the moisture from the steam, the baffle plates also act as skimming means. In boilers which have a tendency to prime, especially 105 in boilers having very small water area, it often happens that a scum or foam will form which in some instances is carried bodily by the steam into the steam pipe where the bubbles composing this foam are shat. 110

tered thus causing the collection of a considerable amount of water in the steam pipes and connections, this water often causing serious hammering in the pipes with the consequent injurious results, and occasionally the bending of a piston rod or breaking of a cylinder head. In the event of a scum or foam being lifted by the steam in this manner, this foam will encounter the baffle plates which will act to effectively shatter the bubbles composing the foam and will separate the moisture thus produced from the steam and collect the same.

Due to the fact that the plates are mounted in overlapping relation, the moisture which collects on the same will flow down the convexed upper surfaces of the plates toward the peripheries of the same, this moisture flowing from plate 8 on to plate 7, and from plate 7 on to plate 6. A suitable collecting pan 9 is secured in the dome 2 immediately beneath and closely adjacent each corner of bottom plate 6. The moisture which flows on to bottom plate 6 as well as the moisture which is collected by this plate, will flow toward the periphery of the plate and about the same and the inner face of the dome to the corners of the plate from which it will be discharged into the collecting pans 9. A drain pipe 10 communicates with each of the pans 9 and is provided with a suitable control valve 11. Each drain pipe discharges into a suitable trap from which the water thus collected is returned to the boiler by a pump, in the usual manner.

By mounting the separating and skimming means directly in the dome the steam is treated so as to remove all moisture before it enters the steam pipes, thus eliminating all danger of moisture being carried into these pipes and the distributing pipes communicating therewith. In this respect my separating and skimming means is materially different from those separators now in use which are mounted outside of the dome and independent therefrom. I have found, by practice, that three baffle plates arranged in the manner shown and described are usually sufficient for a stationary engine of standard construction such as used in connection with steam shovels and the like, though it will be evident that the number of baffles could be varied to suit the particular boiler.

Each of the baffle plates is secured by nut and bolt means to an angle iron frame 12 riveted to the inner face of dome 2. The

inner ends of the plates are held in spaced relation by spacing posts 13 removably secured in the same. By mounting the plates in this manner they may be quickly removed from the dome 2 so as to permit easy access to the interior of the same and the boiler for cleaning, repairing, or other purposes.

It will be evident that there may be slight changes made in the construction and arrangement of the different parts of my invention without departing from the field and scope of the same, and I intend to include all such changes, as fall within the scope of the appended claims, in this application in which a preferred form only of my invention is disclosed.

What I claim is:—

1. In steam skimming and separating means, a boiler, a dome carried by the boiler and communicating with the interior thereof and provided with a steam outlet, a plurality of convexed oppositely directed baffle plates mounted in the dome in superposed spaced relation intermediate said boiler and steam outlet adapted to separate moisture from steam as it flows through the dome, and means for collecting the moisture separated from the steam by said plates and removing it from the dome.

2. In steam skimming and separating means, a boiler, a dome carried by the boiler and communicating with the interior thereof, a plurality of sectoral oppositely directed baffle plates mounted in the dome in superposed spaced relation, said plates being convexed longitudinally, moisture collecting pans mounted beneath and closely adjacent each corner of the lowermost one of said plates, and means for optionally draining said pans.

3. In steam skimming and separating means, a boiler, a dome carried by the boiler and communicating directly with the interior thereof, a plurality of sectoral concavo-convex oppositely directed baffle plates mounted in the dome in superposed spaced relation, each of said plates being concaved in the direction of its longitudinal axis, moisture collecting pans mounted beneath and closely adjacent each corner of the lowermost one of said plates, and means for optionally draining said pans.

In testimony whereof I affix my signature in presence of two witnesses,

CHARLES C. MILLER.
